J. J. Heintzelman,

Truss.

Patented Feb. 16, 1830.

John J. Hantzelman
Gentle Patent

5831x

The Schedule referred to in these Letters Patent and making part of the same containing a description in the words of the said John J. Hantzelman himself of his improvement in the "Spiral Spring Tuff".

The large portion of mankind who are afflicted with this complaint; the great variety of forms in which it appears; the fatality which results from improper treatment & the deficiency hitherto experienced for the want of a good Tuff to confine the Peritoneum or intestines which are the most moveable viscera and occupy the front & lower part of the belly within the parieties of the abdomen; are circumstances which combine to render the investigation of Horner for a radical cure, an instrument to mitigate the distress of those afflicted, by a well adapted Tuff, particularly interesting. Before I describe my Improvement of the spiral Spring Tuff I shall concisely state some of the inconveniences & imperfections of the present construction. They are 4th These in present use consists of a circular steel spring about one inch broad with a small sheet iron plate riveted to the extreme end about four inches in length & about two and a half inches broad in the middle, forming part of an oval on the upper & extreme end, on the lower side from the middle gradually increasing, oblique to the place where it is riveted to the circular spring already described with two small hooks on the outside for fastening the strap of leather which is attached to the covering of the circular spring, so as to secure it on the body.

2nd On the iron plate above described there is a small conning block secured by several nails on which there is placed a parcel of wool or cotton & the whole tuff covered with Muskhair or some other kind of leather with a view of rendering it soft and elastic.

3rd Now it most naturally follows that the Tuff just described loses its elasticity, besides the variety of manners in which the spring is

is frequently prepared paying neither attention nor regard to the tempering of the steel, or frequently allotted to some inexperienced workman or apprentice, or even the formation of the pad & covering which is frequently entrusted to some female for a compensation by no means adequate for the trouble; they are sent into the market without inspection, may scarcely, seen by the manufacturer himself. of this & that the very construction of the above traps enders it useless professing no elasticity, whatever (will at once be admitted by every man of ordinary capacity,) thereby inviting the parts on which it is worn & naturally endangers the life of him who has the misfortune of being afflicted with so distressing & dangerous disease, by not keeping it confined with in its proper place but on the contrary by causing irritation of the pads & the frequent repetitions of protraction, eventually suffer strangulation & close the distressing scene by death. By my improvement which I am about now to describe many if not all of the above dangers & difficulties are obviated which I feel satisfied the most experienced & ingenious will admit. &c. The Spring and pad are here clasped, no iron plates riveted to a circular spring or conny block nailed thereon, or pad clamped to a degree, the hardness thereof equal to the block itself are to be found in "the Spiral Spring Trap". On the contrary a circular spring the length thereof depends on the size of the person with an opening at one end about one & a half inches long, by which means it is attached to a short iron plate about four inches in length & about one & a half inches broad in the middle forming part of an oval on the extreme end & upper part; on the lower side from the middle gradually inclining in an oblique manner to one end of the circular spring with the opening as described above, by this means the spring is fastened on the above described plate by two stationary screws passing thro' the said opening into the plate, should it be at any time necessary to lengthen or shorten the circular spring it is easily accomplished by loosening the screws & putting the circular spring forward or backwards as the person may find it necessary & again fastening the same so that any person of ordinary judgment is able at once to judge the

the requisite length, which is of great importance. On the outside of the small plate as described above there is placed a flat piece of cork with two small holes bored in to admit the spiral springs, which I shall presently describe which comprises them in a firm position when they are covered with leather more than ordinary. In no degree impairs the elasticity thereof in the least, which has been the great dissatisfaction hitherto so anxious to obtain. It will easily be perceived from the position in which these spiral springs are placed which is in addition to that from the former described plate & inserted in another thin plate of the same size and shape which bears immediately on the first, so that when the spiral spring is not worn leaving the spring free they mutually face the two plates about one and a half to two inches apart & contract in ratio as force is applied, being evident, the greater exertion is made by the person it naturally follows, the greater the action should be on the parts & so vice versa & which I believe is happily combined in the principles of the spiral spring trap. In relation to the spiral springs they consist of steel wire of the requisite length to the size of the trap made into a spiral form terminating at each end into the centre, the points turned outwards, the whole being parallel, these points are inserted into a small hole expressly made in each plate in a straight line for the exception of the points affixed at the extremity of each spring as just described, by which means they are kept in their proper places; on the other side of the two plates facing the body, there is another piece of cork, the size of the two plates about a quarter of an inch thick, the centre of which is rather depressed, on this there is placed wool to the thickness of an inch or more, the whole trap is now carefully covered with soft buckskin leather forming, as it were an even surface over the whole plate; having the edges of the leather secured thus, and firmly, sewed to the edges of the two well secured to the external plate answering to which the circular spring is fitted, the whole in appearance when the spiral springs are all set, a ball being inflated on the back of the plate where the circular spring joins the outside plate, there is a small broach fixed which with a leather strap containing

from the covering of the other end of the circular spring is buckled on the body of a moderate tightness which must be obvious call the spiral spring into action producing great elasticity & rotary motion, as the springs are governed altogether by the motion of the body whatever position it is placed in or undue strength is imposed on the parts, at the same time not impairing the mobility of the Truss in the least degree which has been the deficiency of the former one described.

By this improvement I claim every mode of junction of the Truss formed on any union of the spiral or other springs preserving elasticity & rotary motion with a slide in the circular spring for lengthening or shortening the same together with a buckle & stamp for fastening the same around the body which I find to answer perfectly well.
